TUBE SOCKET

Donald R. De Tar, Audubon, N. J., assignor to
 Radio Corporation of America, a corporation of
 Delaware

Application January 30, 1934, Serial No. 708,955

3 Claims. (Cl. 173—328)

My invention relates to electric plug and socket connectors and, more particularly, to sockets for electric discharge devices of the type having connecting pins or prongs extending from the base thereof.

A preferred and well known type of base for electric discharge devices such as vacuum tubes is one having pins extending therefrom which are adapted to make contact on their sides with a socket contact member. One difficulty encountered with the bases of this type has been that, with sockets formerly employed, the tube has a tendency to work out of the socket. This has been true especially in cases where the tube is subjected to considerable vibration or where the tube is supported in a horizontal position or hanging downward.

One object of my invention is to provide a socket of the above-mentioned type which will hold a tube or the like securely in position.

A further object of my invention is to provide a socket of the above-mentioned type which may be produced at a low cost.

A still further object of my invention is to provide a socket of the above-mentioned type which cannot easily be damaged in use.

In a preferred embodiment of my invention, each socket contact member consists of an inverted U-shape member of resilient material having good conductivity, and a cantilever steel spring arranged to force one leg of said U-shaped member against a tube pin or prong. The said leg of the U-shaped member is so shaped that the contacting pin makes contact near the bottom or base of the U whereby the tube cannot readily work or shake out of contact with the socket contact members.

Other objects, features, and advantages of my invention will appear from the following description taken in connection with the accompanying drawing, in which,

Figure 1 is a side view of a socket, embodying my invention and having a vacuum tube inserted therein,

Figure 2 is a fragmentary view of the socket and tube of Figure 1 showing the position of a pin as it is being inserted into the socket,

Figure 3 is a view taken on the line 3—3 of Figure 1, and

Figure 4 is a perspective view on an enlarged scale of one of the contact members shown in Figure 1.

Referring to Figure 1, a vacuum tube 1 of conventional construction comprising a base 3 having contact pins 5 extending therefrom is shown

inserted in position in my improved socket. The socket comprises a plate 7 of insulating material, such as Micarta, having a plurality of openings 9 therein through which the tube contact pins 5 may be inserted.

Adjacent to each opening 9 there is fastened a socket contact device which consists of a substantially U-shape contact member 11 of springy material such as phosphor bronze and a reinforcing or backup spring 13. Referring to Figure 4 where the socket contact device is shown more clearly, it will be seen that the U-shape member 11 consists of a base portion 11a and two leg portions 11b and 11c, leg portion 11b being positioned to make contact with a contact pin 5 (indicated in dotted lines) and having a slot 15 therein for providing a sharp wiping edge with which the pin 5 makes contact. This leg of the contact member is bent rather sharply near the base portion 11a so that the contact pin 5 will engage the leg at this bent portion, as shown in Figure 1, rather than at the outer end of the leg.

In the leg portion 11c there is a portion 17 which is punched out of alignment with the main section of the leg in order to facilitate soldering 25 or otherwise connecting conductors to the contact member 11.

The reinforcing spring 13, which is preferably made of thin sheet steel heat treated to a spring temper, has a base portion 13a and a spring portion 13b bent at an angle thereto and tapering towards its end. The free end of the base portion 13a is provided with a short tab 19 which, together with the narrow end portion of the spring portion 13b, is utilized for centering 35 or aligning the spring 13 with respect to the contact member 11 during assembly.

Also for the purpose of alignment, the contact member 11 is provided with an opening 21 at the bottom of the leg portion 11c and with a notch 23 at the top of the leg portion 11b.

The socket is assembled by placing the spring 13 inside the U-shaped member 11 with the base portions of the spring 13 and member 11 in contact with each other, and with the tab 19 and the end of the spring portion 13b engaging the opening 21 and the notch 23, respectively. The spring 13 and contact member 11 are then riveted or otherwise suitably fastened to the bottom of the plate 7 in such a position with respect to an opening 9 that the bent section of the leg portion 11b is located underneath a portion of the opening.

Figure 2 shows the relative positions of the socket elements and a contact pin 5 just as the

pin is being inserted into the socket. By comparing this figure with Figure 1, it will be seen that as the pin 5 is moved into position, both the contact member 11 and the spring 13 are forced away from the opening 9 whereby the pin 5 makes contact with the contact member 11 only at the bend in the leg portion 11b. Also by referring to Figure 3, it will be seen that the pin 5 makes contact with the edges of the slot 15 so that there is a wiping or cleaning action on the pin as it is moved into or out of the socket.

One of the main advantages in having the pin make contact with the contact member 11 at a point near the plate 7 rather than at a point near 15 the end of the leg portion 11b or along its entire length, is that the tube is held more securely in position. One reason for this is that the force exerted against the pin with a given spring force is increased due to lever action as the point of 20 contact of the member 11 and the pin 5 is moved closer to the plate 7. Therefore, there is less tendency for the tube to be shaken out of the socket by vibrations such as may be encountered in shipping the apparatus. Furthermore, even 25 if the tube is shaken part way out of the socket, its pins will still be held in good contact relation with the contact members 11 since the contact was originally being made at a point near the base end of each pin 5 rather than at a point 30 near its outer end.

A still further advantage in the above described structure is that with a pin 5 making contact with a contact member 11 at a point near the base of a leg portion 11b and with the reinforcing spring 35 13 making contact with the leg portion 11b at its end, the spring 13 will hold the contact member 11 against the pin with a greater force than in the case of conventional socket designs. That this is true will be apparent by considering the leg portion 11b as a lever having its fulcrum point at the plate 7 and having the force of spring 13 applied at the opposite end of the lever. Since the point at which force is applied to the pin is closer to the fulcrum point than to the other end 40 of the lever, the force applied to the leg portion 11b by spring 13 is multiplied by the lever action when applied to the pin, and a spring 13 of medium stiffness insures good contact.

The above-described spring arrangement also 50 prevents possible damage to the socket since it restores the contact leg 11b to its original position in the event that the tube is inserted at such an angle in the socket that it bends the portion 11b past its elastic limit.

55 Various modifications may be made in my in-

vention without departing from the spirit and scope thereof and I desire, therefore, that only such limitations shall be placed thereon as are necessitated by the prior art and are set forth in the appended claims.

I claim as my invention:

1. In a socket for a device having a contact pin, a plate having an opening therein for said pin, a contact member having a base portion and an arm portion having a free end, means for fastening said base portion to said plate at a point near said opening, said arm portion extending away from said plate, said contact member being so positioned that said arm portion extends over a portion of said opening, said arm portion being so shaped that at a point nearer said base than the free end of said arm portion it extends farther over said opening than at its free end both before and after said pin is forced into contact with said arm, and a separate auxiliary spring 20 fastened to said plate and having a base portion superimposed upon the base portion of said contact member and an arm portion positioned with its end in slidable contact with the end of said arm portion of said contact member. 25

2. In a socket for a device having a contact pin, a plate having an opening therein, a contact member fastened to said plate at a point near said opening, said member having a portion bent away from said plate whereby there is a bend in 30 said portion, said bend being nearer said plate than the end of said portion, said member being so positioned that said bend extends farther over said opening than any other part of said portion whereby a contact pin inserted into said opening 35 makes contact with said member at said bend, and a separate spring member fastened to said plate and so positioned that its free end makes contact with and only with the end of said portion to force said bend against a contact pin. 40

3. In a socket for a device having a contact pin, a plate having an opening therein, a substantially U-shaped contact member having an opening at the base of one leg of said U and having a notch in the end of the other leg of said U, a spring 45 having a base portion and a spring portion which is at an angle to said base portion, said base portion having a tab on the free end thereof, said spring being positioned inside said contact member with said tab in said opening and with the 50 free end of said spring portion in said notch, and means for fastening said spring and said contact member to said plate at a point near said opening.
